[57] **ABSTRACT**

In apparatus for driving a piezoelectric ceramic element by applying a driving voltage across a pair of driving electrodes of the ceramic element, there are provided a phase detector connected to one driving electrode for detecting the phase of the current flowing through the ceramic element as a voltage phase, an amplifier connected to the other driving electrode for supplying thereto a driving voltage, and a phase shifter to positively feed back the output from the phase detector to the amplifier for coinciding the voltage phase and the current phase of the ceramic element so as to drive the same at the most suitable driving frequency.

DRIVING APPARATUS FOR PIEZOELECTRIC CERAMIC ELEMENTS

BACKGROUND OF THE INVENTION

This invention relates to apparatus for driving a piezoelectric ceramic element.

A piezoelectric ceramic element generally comprises a rectangular substrate essentially consisting of a piezoelectric substance such as barium titanate (BaTiO_3) or lead zirconate titanate [$\text{Pb}(\text{ZrTi})\text{O}_3$] and a pair of driving electrodes disposed on the opposite sides of the substrate. A predetermined driving voltage is impressed across the driving electrodes for resonating the ceramic element to vibrate at the natural frequency of the substrate. It is well known in the art that the ceramic element operates at its highest efficiency when it is excited with a driving voltage having substantially the same frequency as the natural frequency. In this case, the ceramic element can be used as a source of ultrasonic oscillation, and where an output electrode is mounted on the ceramic element, it can be used as a high voltage generator.

Considering the general characteristics of a ceramic element, an equivalent circuit thereof as seen from the side of the driving electrodes may be represented by an inter-electrode capacitance C_0 , and a plurality of parallel connected series circuits each including an equivalent inductor L_i , an equivalent capacitor C_i and an equivalent resistor R_i (where $i = 1, 2, \dots, n$), as diagrammatically shown in FIG. 1 of the accompanying drawing. Each one of the series circuits connected in parallel with the capacitance C_0 resonates only at a driving frequency of $n/2 f_0$ (where n is an integer, and f_0 represents the natural frequency of the ceramic element), thus producing a high voltage at the output side of the ceramic element where it is used as a high voltage generator. Voltage step-up action is especially remarkable when the driving frequency equals $\frac{1}{2} f_0$ or f_0 . When the ceramic element resonates with the series circuits of the equivalent circuit shown in FIG. 1, the drive impedance of the ceramic element as seen from the driving side becomes a minimum and the phase becomes zero. Where the element resonates with a parallel circuit comprising the inter-electrode capacitance C_0 and the series circuits the drive impedance of the ceramic element as seen from the driving side becomes a maximum and the phase becomes zero in the same manner as the series resonance mentioned above.

Considering the phase characteristic of the ceramic element, the current phase advances $\pi/2$ with respect to the voltage phase at the non-resonance frequency, as shown in FIG. 2. However, at the resonance frequency, the phase difference between voltage and current becomes zero. As the frequency exceeds by a little the resonance frequency the voltage phase advances $\pi/2$ with respect to the current phase and both phases become zero again at the anti-resonance point. Thereafter, only the phase of the current advances.

FIG. 3 illustrates curves showing the relationship between the frequency and the drive impedance characteristic Z_i and the voltage step-up ratio V_o/V_i in which the curve a represents the drive impedance characteristic which becomes minimum at resonance frequencies $\frac{1}{2} f_0, f_0, \dots$ and becomes maximum at the anti-resonance frequencies. Like the drive impedance characteristic, the voltage step-up characteristic b becomes maximum at the resonance frequencies.

In other words, the ceramic element provides the maximum voltage step-up ratio at the resonance frequency (or natural frequency of vibration) and the drive impedance at this time as seen from the driving side becomes minimum. Moreover, the phases of the voltage and current impressed across the ceramic element become equal.

However, the natural frequency of the ceramic element varies in dependence upon the temperature of the ceramic element itself (that is the ambient temperature and the heat generated in the element by the operation thereof), the error in the configuration of the ceramic element, load variation and the DC voltage applied across the driving electrodes. This tendency is especially remarkable when the ceramic element is driven at a frequency different from the natural frequency thereof. Furthermore, a phase difference will appear between the applied driving voltage and the current flowing through the ceramic element, thus deviating from the most suitable driving frequency (that is the frequency providing the highest conversion frequency) and the most suitable phase which are determined under a definite temperature condition whereby the output of the ceramic element is greatly reduced.

The result of experiment shows that the resonance frequency of the ceramic element increases with the temperature thereof as shown in FIG. 4 and also with the load R_L as shown in FIG. 5.

SUMMARY OF THE INVENTION

It is therefore an object of this invention to provide an improved apparatus for driving a piezoelectric ceramic element.

Another object of this invention is to provide a novel driving apparatus capable of operating a piezoelectric ceramic element at a high efficiency.

Still another object of this invention is to provide a driving apparatus for a piezoelectric element for causing it to operate stably irrespective of the variation in the operating conditions.

A further object of this invention is to provide apparatus for driving a piezoelectric ceramic element which has a simplified construction but can operate the element at a high efficiency.

According to this invention for use with a piezoelectric ceramic element including a pair of driving electrodes for applying a driving voltage across the driving electrodes to cause the piezoelectric ceramic element to resonate at the natural frequency thereof, there is provided driving apparatus comprising a phase detector connected to one driving electrode for detecting the phase of the current flowing through the ceramic element as a voltage phase, an amplifier connected to the other driving electrode for supplying thereto a driving voltage, and a phase shifter to positively feed back the output from the phase detector to the amplifier for coinciding the voltage phase and the current phase of the ceramic element so as to drive the same at the most suitable driving frequency.

BRIEF DESCRIPTION OF THE DRAWINGS

Further objects and advantages of the invention will become apparent from the following detailed description taken in connection with the accompanying drawing in which:

FIG. 1 shows an equivalent circuit of a piezoelectric ceramic element as viewed from the side of the driving electrodes;

FIG. 2 is a graph showing a frequency-phase characteristic of a piezoelectric ceramic element;

FIG. 3 shows a drive impedance characteristic (curve *a*) and a voltage step-up characteristic (curve *b*) of a piezoelectric ceramic element;

FIG. 4 is a plot showing a resonance frequency-temperature characteristic of a piezoelectric ceramic element;

FIG. 5 is a plot showing a resonance frequency-load characteristic of a piezoelectric ceramic element;

FIG. 6 is a connection diagram of one embodiment of the novel apparatus for driving a piezoelectric ceramic element;

FIGS. 7A and 7B show different examples of the phase shifter;

FIG. 8 is a graph showing the frequency-phase characteristics of a piezoelectric ceramic element and a phase shifter and is useful to explain the operation of the novel driving apparatus;

FIG. 9 shows a detailed connection diagram of the novel driving apparatus;

FIG. 10 is a plot showing a measured temperature-frequency characteristic of a piezoelectric ceramic element;

FIG. 11 is a plot showing a temperature-electrostatic capacitance characteristic of a capacitor utilized to constitute a phase shifter;

FIG. 12 shows a modified phase shifter and a modified phase detector and

FIGS. 13A and 13B show still other modifications of the phase detector.

DESCRIPTION OF THE PREFERRED EMBODIMENTS

In FIG. 6 of the accompanying drawing, there is shown a preferred embodiment of the novel apparatus for driving a piezoelectric ceramic element, more particularly a self excitation oscillation driving apparatus for a piezoelectric ceramic element constructed to act as a high voltage generator. The ceramic element 10 shown in this figure comprises a pair of driving electrodes 10a and 10b and an output electrode 10c. The arrangement of the electrodes simplifies the construction of the ceramic element and of the associated circuit. One of the driving electrodes 10a is connected to the output terminal 11b of an amplifier 11 which may be a conventional amplifier circuit comprised by a transistor or a vacuum tube. However, in order to improve the transmission efficiency a B-class or an AB-class amplifier circuit is preferred. The other driving electrode 10b is connected to a phase detector 12. The phase detector 12 includes a resistance or a reactance element of a value which does not provide a load division effect when the ceramic element is driven. Thus for example, where the ceramic element has a resistance of about 600 ohms, the phase detector is designed to have a resistance of less than 50 ohms. The driving electrode 10b is also connected to the input terminal 13a of a phase shifter 13 with its other side 13b connected to the input terminal of amplifier 11.

The purpose of phase shifter 13 is to compensate for the lead or lag of the phase of the current flowing through ceramic element 10 with respect to the phase of the output voltage from amplifier 11, thereby oper-

ating the ceramic member 10 at the point of zero phase difference. Preferably, it is advantageous to so construct the phase shifter 13 that it compares the phase of the driving voltage applied across the ceramic member with the phase of the current flowing therethrough while at the same time can adjust the degree of lead or lag in the phase. The output electrode 10c of the ceramic element 10 is connected to a load 15 via a rectifier circuit 14 comprising diodes 14a and 14b.

Above described phase detector 12, amplifier 11 and phase shifter 13 cooperate to constitute the novel driving apparatus 16 for the ceramic element.

The driving apparatus described above operates as follows;

The current flowing through the ceramic element 10 is detected as the voltage appearing across phase detector 12, and this voltage is fed back positively to amplifier 11 through phase shifter 13. Accordingly the driving apparatus 16 comprising amplifier 11 and phase shifter 12 undergoes a self-excited oscillation thus causing the ceramic element 10 to vibrate at the natural frequency thereof which is the most suitable driving frequency. Under these conditions, it is possible to make equal the phase of the driving voltage of the ceramic element and the phase of the current flowing therethrough because it is possible to set the (phase shift) of an LC or RC circuit constituting the phase shifter 13 to be sufficiently smaller than the θ (phase shift) of the ceramic transformer.

When the operating conditions for the continuous operation of the ceramic member are preset, it is possible to construct the phase shifter as a simple combination of a capacitor and a resistor as shown in FIGS. 7A and 7B.

According to this invention it is also possible to compensate for the phase lag caused by amplifier 11 by the action of phase shifter 13. Thus for example, where amplifier 11 includes resonance circuit of large α , the phase of the output voltage lags with respect to the phase of the input voltage. In this case, the phase shifter 13 is designed to include a phase advancing circuit.

Inherently, the ceramic element is a mechanically vibrating member having a resonance frequency of $n/2 f_0$, as above described. For this reason, mere driving of the ceramic element results in the variation at the resonance frequency, thus greatly reducing the output power. To obviate this difficulty, a LC filter circuit or RC filter circuit of a relatively low value of α or a resonance circuit is included in the amplifier 11 to cause only longitudinal vibration of the ceramic element. This assures an efficient operation of the ceramic element. Inclusion of a resonance circuit in amplifier 11, however results in phase rotation thus causing the phase of the output voltage to advance with respect to the phase of the input voltage to the amplifier. In such a case, it is necessary to use a phase shifter having a phase delay characteristic.

Also this arrangement can compensate for the variation in the resonance frequency of the piezoelectric ceramic element caused by temperature variation. In this case, phase shifter 13 can be composed of a circuit comprising an inductor L and a capacitor C or a circuit comprising a capacitor C and a resistor R (see FIG. 7). As the resonance frequency f_0 of the ceramic element 10 varies with temperature, a phase difference will be created between the driving voltage impressed across the ceramic element and the current flowing there-

through. This phase difference can be compensated for thus assuring the voltage and current to have the same phase since the circuit constant of phase shifter 13 varies in accordance with the temperature as will be described hereunder with reference to FIG. 8. As can be noted from characteristic curves *a* and *b* (curve *a* represents the frequency-phase characteristic of the ceramic member and curve *b* the frequency-phase characteristic of the phase shifter), at a given temperature, the center frequency F_o of the phase shifter is shifted by f_1 from the resonance frequency f_o of the ceramic element 10. Moreover, the phase shifter 13 is set such that it provides a phase delay θ_1 with respect to the phase at the resonance frequency of the ceramic element.

When the ambient temperature rises the characteristic *a* of the ceramic element shifts to *a'* while the resonance frequency f_o shifts to $f_o + \Delta f_2$ by an increment Δf_2 . At the same time, the phase is varied to θ_2 by an increment $\Delta\theta$. Due to this temperature variation, the characteristic of the phase shifter 13 is shifted from *b* to *b'* and its center frequency is shifted from F_o to Δf_2 . In other words, frequency difference between the resonance frequency f_o and the center frequency F_o , or the amount of phase compensation θ_1 is independent of the temperature variation. For this reason, it is possible to operate the ceramic element under the most suitable condition over a wide range of temperature variation.

FIG. 9 shows the details of the novel driving apparatus 16 which is used to drive the piezoelectric ceramic element 10 acting as a solid state transformer for generating high voltage. Circuit elements corresponding to those shown in FIG. 6 are designated by the same reference numerals. Driving electrode 10b is connected to an intermediate tap 17a₁ of the primary coil 17a of an input transformer 7 having primary and secondary coils 17a and 17b and a movable core 17c made of ferrite, for example, for adjusting the coupling between the primary and secondary coils as well as the inductances thereof. The part of the primary coil 17a above the intermediate tap 17a₁ acts as part of the phase shifter 13 with the remainder of the primary coil 17a comprising the phase detector 12. The primary coil 17a is connected in parallel with a capacitor 18 having one end grounded. The upper part of primary coil 17a and capacitor 18 comprises phase shifter 13 and their values are selected to coincide the phases of the driving voltage impressed across the ceramic element 10 and of the current flowing therethrough. Fine adjustment of the phase is provided by the axial movement of core 17c of input transformer 17 for varying the inductance of the primary coil 17a. One terminal 17b₁ of the secondary coil 17b of input transformer 17 is connected to the base electrode 20b of an excitation power transistor 20 for the ceramic element via a resistor 19. The other end 17b₂ of the secondary coil 17b is grounded through a parallel combination of a biasing diode 21 and a bypass capacitor 22. This end 17b₂ is also connected to a source of direct current +B through a resistor 23. The collector electrode 20c of transistor 20 is connected to the base electrode 20b through a serially connected resistor 24 and capacitor 25. On the other hand, collector electrode 20c is connected to DC source +B via the primary winding of an output transformer 26 having primary and secondary windings 26a and 26b. Further, the collector electrode 20c is grounded through a damper diode 27. The emitter electrode 19e of transistor 19 is grounded through a stabilizing resistor 28.

Above described component elements constitute the amplifier 11 shown in FIG. 6. In this arrangement, the by-pass capacitor 22 is used for creating easy oscillation of amplifier 11 whereas resistors 19, 24 and capacitor 25 are used to suppress the self-oscillation of transistor 20.

As transistor 20 is used a suitable transistor having a high reverse breakdown voltage and a frequency characteristic permitting self-excited oscillation of about 60 10 KH_z. The damper diode 27 connected in the forward direction to the collector electrode 20c functions to absorb the reverse voltage caused by the leakage inductance of output transformer 26 whereby to prevent damage of transistor 20. One end of the secondary 15 winding 26b of output transformer 26 is grounded whereas the other end is connected to the driving electrode 10a of the ceramic element 10.

When the ambient temperature of the apparatus (the temperature of the environment in which the apparatus 20 is located) varies, the resonance frequency f (KH_z) of the ceramic element 10 increases with the increase in temperature as shown in FIG. 10. At this time, however, the characteristic of phase shifter 13 constituted by the primary coil 17a of input transformer 17 and capacitor 18 varies also in accordance with the variation in the characteristic of the ceramic element 10. More 25 specifically, the inductance L of the primary coil 17a varies in accordance with the temperature characteristic of the core 17c of input transformer. In the same manner, the capacitance C of capacitor 18 varies to follow the temperature variation. Accordingly, it is possible to compensate for the temperature variation by designing the circuit constant of the phase shifter 13 to be 30 consistent with the temperature characteristic of the ceramic member.

In an experiment utilizing the circuit shown in FIG. 9, the variation in inductance L with respect to the temperature variation was rather complicated so that the 35 number of turns of the primary coil 17a was reduced as far as possible for the purpose of reducing inductance L and the capacitance of capacitor 18 was increased correspondingly. As a result, the resonance frequency of phase shifter 13 varied substantially in accordance with the temperature characteristic of capacitor 18. To 40 this end, a capacitor was used whose electrostatic capacitance C (microfarad) decreases with the rise in temperature t (°C) as shown in FIG. 11.

Although in the embodiment shown in FIG. 9, a two 45 winding transformer was used to constitute the phase shifter and phase detector, it is to be understood that it is also possible to use a three winding transformer 31 as shown in FIG. 12. The coil 31a is used to comprise the phase detector 12, coil 31b to comprise the phase shifter 13 in combination with capacitor 32 and coil 31c is used to supply power to an amplifier, not shown, in the succeeding stage. Further, although phase detector 12 has been described as comprising a resistance element or a reactance element it may comprise an 50 emitter grounded type transistor 40 having its base electrode directly connected to driving electrode 10b of the ceramic element and its collector connected to phase shifter 13, as shown in FIG. 13A. Alternatively, as shown in FIG. 13B, the phase detector may be 55 constituted by a base grounded type transistor 41 with its emitter electrode connected directly to the driving electrode 10b of the ceramic member and the collector electrode to the phase shifter 13.

Although the invention has been described in connection with a piezoelectric ceramic element constructed to act as a high voltage generator, it will be clear that the novel driving apparatus can also be applied to a piezoelectric ceramic element acting as a source of ultrasonic waves.

The invention is not limited to the particular embodiments illustrated but many changes and modifications may be made without departing the scope of invention as defined in the accompanying claims.

What is claimed is:

1. Driving apparatus for driving a piezoelectric ceramic element including a pair of driving electrodes wherein a driving voltage is impressed across said driving electrodes for resonating said piezoelectric ceramic element at the natural frequency thereof, said driving apparatus comprising a phase detector connected to one of said driving electrodes for detecting the phase of the current flowing through said ceramic element as a voltage phase, an amplifier connected to the other driving electrode for supplying thereto a driving voltage, and a phase shifter to positively feed back the output from said phase detector to said amplifier for coinciding the voltage phase and the current phase of said ceramic element so as to drive said ceramic member at the most suitable driving frequency, said amplifier comprising an input transformer connected to the output of said phase detector, a transistor connected to the output of said transformer, an output transformer connected to the output of said transistor and means for connecting the driving electrodes of said piezoelectric ceramic element across the output of said output transformer.

2. Driving apparatus for driving a piezoelectric ceramic element including a pair of driving electrodes wherein a driving voltage is impressed across said driving electrodes for resonating said piezoelectric ceramic element at the natural frequency thereof, said driving apparatus comprising a phase detector connected to one of said driving electrodes for detecting the phase of the current flowing through said ceramic element as a voltage phase, an amplifier connected to the other driving electrode for supplying thereto a driving voltage, and a phase shifter to positively feed back the output from said phase detector to said amplifier for coinciding the voltage phase and the current phase of said ceramic element so as to drive said ceramic member at the most suitable driving frequency, said driving apparatus including a three winding transformer, a first winding thereof comprising said phase detector, a second winding comprising said phase shifter and a third winding being utilized as an output winding and connected to said amplifier, said phase shifter further including a capacitor connected to said second winding.

3. Driving apparatus for driving a piezoelectric ceramic element including a pair of driving electrodes wherein a driving voltage is impressed across said driving electrodes for resonating said piezoelectric ceramic element at the natural frequency thereof, said driving apparatus comprising a phase detector connected to one of said driving electrodes for detecting the phase of the current flowing through said ceramic element as a voltage phase, an amplifier connected to the other driving electrode for supplying thereto a driving voltage, and a phase shifter to positively feed back the output from said phase detector to said amplifier for coinciding the voltage phase and the current phase of said

ceramic element so as to drive said ceramic member at the most suitable driving frequency, said phase detector comprising an emitter grounded type transistor, the base electrode thereof being connected directly to the driving electrode of said ceramic element and the collector electrode being utilized to derive an output and connected to said phase shifter.

4. Driving apparatus for driving a piezoelectric ceramic element including a pair of driving electrodes wherein a driving voltage is impressed across said driving electrodes for resonating said piezoelectric ceramic element at the natural frequency thereof, said driving apparatus comprising a phase detector connected to one of said driving electrodes for detecting the phase of the current flowing through said ceramic element as a voltage phase, an amplifier connected to the other driving electrode for supplying thereto a driving voltage, and a phase shifter to positively feed back the output from said phase detector to said amplifier for coinciding the voltage phase and the current phase of said ceramic element so as to drive said ceramic member at the most suitable driving frequency, said phase detector comprising a base grounded type transistor, the emitter electrode thereof being connected directly to the driving electrode of said ceramic element and the collector electrode being utilized to derive out an output and connected to said phase shifter.

5. Driving apparatus for driving a piezoelectric ceramic element including a pair of driving electrodes wherein a driving voltage is impressed across said driving electrodes for resonating said piezoelectric ceramic element at the natural frequency thereof, said driving apparatus comprising a phase detector connected to one of said driving electrodes for detecting the phase of the current flowing through said ceramic element as a voltage phase, an amplifier connected to the other driving electrode for supplying thereto a driving voltage, and a phase shifter to positively feed back the output from said phase detector to said amplifier for coinciding the voltage phase and the current phase of said ceramic element so as to drive said ceramic member at the most suitable driving frequency, said driving apparatus including a transformer whose secondary winding is connected to said amplifier and whose primary winding is provided with an intermediate tap, said phase detector comprising one portion of said primary winding between said intermediate tap and one end of said primary winding, said phase shifter comprising the other portion of said primary winding and a capacitor connected thereto.

6. Driving apparatus for driving a piezoelectric ceramic element including a pair of driving electrodes wherein a driving voltage is impressed across said driving electrodes for resonating said piezoelectric ceramic element at the natural frequency thereof, said driving apparatus comprising a phase detector connected to one of said driving electrodes for detecting the phase of the current flowing through said ceramic element as a voltage phase, an amplifier connected to the other driving electrode for supplying thereto a driving voltage, and a phase shifter to positively feed back the output from said phase detector to said amplifier for coinciding the voltage phase and the current phase of said ceramic element so as to drive said ceramic member at the most suitable driving frequency, said phase shifter having a center frequency which shifts in response to temperature variations in the environment of said ap-

paratus to compensate for the effect of said temperature variations on the resonance frequency of said piezoelectric ceramic element.

7. The driving apparatus as recited in claim 6 wherein said phase shifter comprises a resonance circuit including a capacitor and an inductor connected thereto, the resonant frequency of said resonance circuit varying substantially in accordance with the effect of said tem-

perature variations on said capacitor.

8. The driving apparatus as recited in claim 6 wherein said phase shifter comprises a resonance circuit including a capacitor and an inductor connected thereto, the resonant frequency of said resonance circuit varying in dependence on the effect of said temperature variations on said inductor.
